PERISCOPE INSTALLATION

Lawrence Y. Spear, New London, Conn., assignor
to Electric Boat Company, Groton, Conn., a
corporation of New Jersey

Application July 21, 1934, Serial No. 736,291

8 Claims. (Cl. 114—16)

This invention relates to submarine boats, and has to do with periscope installations.

It is the usual practice in submarine boat construction to provide, near the middle of the length of the boat, a central operating compartment or control room containing the diving station and many other installations which it is necessary to use in trimming the boat for diving, and in diving and submerged navigation. The conventional 10 conning tower is located over this central operating or control compartment and is surrounded by a fairwater to reduce the submerged resistance. On top of the tower and fairwater, it is customary to fit a navigating bridge for surface operation. The periscopes, which constitute a vital element in submerged navigation, are always fitted in this part of the boat. These instruments work through stuffing boxes and are provided with hoisting and lowering gear to permit of regulating the height of the objective lens above the ship structure. Ordinarily, the eye-piece of one periscope is located in the conning tower, and that of the other periscope in the control room below. The object of locating one 20 periscope in the conning tower is to secure the maximum possible height for the periscope objective lens above the structure of the ship when the periscope is fully extended. In some cases, however, the eye-pieces of both periscopes have been 30 located in the control room.

It is known to provide an operating platform which moves up and down with the periscope, and such a platform has been fitted to conning tower periscopes in some submarines. When a platform 35 is fitted in this manner to a conning tower periscope, it is necessary to provide a trunk below the conning tower into which the operating platform and the operator descend when it is desired to use the periscope at low elevation, which is usually necessary with conning tower periscopes except at low speeds, due to the vibration of the periscope caused by passage of the instrument through the water at high speeds. Such an arrangement forces the adoption of the conning 40 tower, instead of the control room, as the normal operating station for the commanding officer. This is objectionable in that it involves the duplication of various instruments and apparatus in the control room and conning tower. The trunk 45 below the conning tower is objectionable, since it must be disposed within the control room or compartment, which is already crowded, where it takes up valuable space and obstructs observation of the several stations in this compartment. In 50 addition, when operating with the periscope at

low elevation, direct communication is cut off from the central operating or control compartment and observation, by the commanding officer, of the instruments either in the conning tower, or in the central control compartment, is impossible. 5

It is an object of my invention to provide a periscope installation of comparatively simple construction and operation in which the operating officer has direct communication at all times with the control compartment and, when operating the periscope at low elevation, can observe directly the stations and instruments in said compartment. A further object is to provide a periscope installation of the character stated which permits of the periscope being projected to at least 10 as great a height as in the present type of conning tower periscope above referred to. Another object is to provide a periscope installation which does not objectionably obstruct the interior of the control compartment or interfere with observation of the various stations and instruments 15 therein. Further objects and advantages of my invention will appear from the detail description.

In the drawings:—

Figure 1 is a fragmentary vertical sectional view 25 of the mid-ship portion of a submarine boat, taken fore and aft, embodying the periscope installation of my invention;

Figures 2 and 2A, taken together, constitute a central vertical sectional view, on an enlarged 30 scale, through a periscope installation embodying my invention;

Figure 3 is a section taken substantially on line 3—3 of Figure 2;

Figure 4 is a detail underneath view, on an enlarged scale, of the cover for the lower end of the periscope trunk; 35

Figure 5 is a section taken substantially on line 5—5 of Figure 2A;

Figure 6 is a section taken substantially on line 40 6—6 of Figure 2A showing the cable winding drum and associated parts;

I have illustrated my invention, by way of example, as applied to a submarine boat having no conning tower proper, the construction of this 45 boat being, in general, quite similar to that disclosed in Patent No. 1,793,796, issued February 24, 1931, to Hugo E. Grieshaber, for Bridge support for submarines. The boat B comprises a hull 1, the interior of which is divided into various compartments and tanks in a known manner. The hull 1 is watertight and pressure resistant and is frequently referred to as the "hull" or, in naval parlance, as the "strong hull". Either of these 50 terms is commonly accepted in the art as refer- 55

ring to the watertight and pressure resistant hull exclusive of the superstructure, bridge, and other appurtenances. A control compartment 2 is provided at the midship portion of the hull and 5 contains the various apparatus for use in navigating the boat, particularly when submerged, including diving station 3, master gyrocompass 4, etc. An access trunk 5 is mounted on the top 6 of pressure hull 1 and serves to support, in part, 10 a navigating bridge 7 for surface operation, this trunk giving access to the bridge from the interior of compartment 2. A ladder 8 within compartment 2 provides access from the latter to trunk 5. Trunk 5 is, in general, of known construction, being 15 provided at its lower end with a watertight and pressure-resistant closure or cover 9.

A periscope 10 is slidably mounted through top 6 of pressure hull 1 and through an offset 11 of trunk 5. The eyepiece of this periscope is at all 20 times within compartment 2, in the use of the periscope, this periscope being used at relatively low elevation only. The periscope 10 may be raised and lowered in any suitable or known manner, and, when in full lowered position has its lower portion 25 stored in a suitable housing 12 within hull 1. The installation of periscope 10 is of known type and need not be illustrated nor described in detail.

A watertight and pressure-resistant trunk 13, 30 of substantially cylindrical shape, extends through and above top 6 of hull 1 and, in part, supports the navigating bridge 7. This trunk opens directly, at its lower end, into compartment 2 at the top thereof. A suitable cover 14 (Figure 2) is provided within trunk 13 and has a gasket 35 15 mounted in its under face for seating upon upwardly projecting flange 17 for effecting a watertight and pressure-resistant closure therewith when the cover is in its full lowered position.

A periscope 18 is slidably mounted through 40 cover 14 centrally thereof, and through the top of trunk 13 and the deck of navigating bridge 7, this periscope operating through suitable stuffing boxes 19 and 20 carried by cover 14 and the top of trunk 13, respectively, for providing watertight 45 closures about the periscope while permitting upward and downward movement thereof. A yoke 21 is secured about periscope 18 below cover 14 and at the upper face of a collar 22 extending about the periscope a short distance above eyepiece 23 thereof. The yoke 21 contacts arcuate stops 24 projecting from the under face of cover 14, in the upward movement of the periscope, for moving the cover upward with the periscope after the latter has been raised to a predetermined extent. Suitable handles 25 are pivotally secured 50 to the lower end of periscope 18 for turning the latter in the use thereof, these handles being positionable, when not in use, in substantial parallelism with the periscope and in contact therewith, as indicated in Figure 2.

A housing trunk 27 is disposed within hull 1 and extends from the bottom 28 thereof upward through intermediate deck 29, opening into compartment 2 at the bottom thereof, this trunk 27 being disposed coaxial with trunk 13 and periscope 18. An operating platform 30 is rigidly secured to and suspended from cover 14 by stanchions 31. This platform comprises a central collar 32 disposed coaxial with periscope 18 60 and of a size to accommodate the latter when the handles 25 are turned into inoperative position. Stanchions 33 are secured at their upper ends to collar 32 and are slidable through guide brackets 34 suitably secured to the inner face of trunk 27 70 adjacent the upper end thereof. The lower ends 75

of stanchions 33 are secured to a guide ring 35 fitting the interior of trunk 27 and slidable therein. The brackets 34 and stanchions 33 are spaced apart to accommodate periscope 18, the lower portion of which, when in its fully retracted position, is housed within trunk 27, as indicated in Figure 2A.

A drum 36 is rotatably mounted within hull 1 adjacent the lower end of trunk 27 and to one side thereof. Two cables 37 are secured at one 10 end to the drum 36 and are windable onto and off of the end portions of the latter. A third cable 38 is secured at one end to the drum and is windable onto and off of the central portion thereof in opposite relation to the cables 37. 15 Each of the cables 37 is led through trunk 27 and about a sheave 39 loosely mounted on a shaft 40 suitably supported in the lower portion of trunk 27. Cables 37 each extend upward within trunk 27 and over and under two sheaves 42 supported 20 by a bracket 42a suitably secured to deck 29 adjacent the upper end of trunk 27. The cables 37 extend upward from sheaves 42 through stuffing boxes 43 in flange 17a at the lower end of trunk 13, and thence upward within the trunk and over pairs of sheaves 44 supported by brackets 45 secured to the top of trunk 13, these cables extending downward from the inner sheaves 44 adjacent and parallel to periscope 18 and through stuffing boxes 46 in cover 14, the other ends of cables 37 being anchored in yoke 21 in a known manner. Stuffing boxes 43 and 46 are of known construction and are of a character such that the cables pass readily therethrough in the normal adjustment of the stuffing boxes, but can be tightened up so as to form watertight and pressure-resistant closures about the cables when necessary. Cable 38 is led into trunk 27, about a sheave 47 loosely mounted on shaft 40, and thence upward to the lower end of periscope 18 40 to which the upper end of this cable is suitably anchored.

When the drum 36 is rotated in one direction, cables 37 are wound thereon for raising the yoke 21 and, with it, the periscope 18 and cover 45 14, the extreme upper position of these parts being indicated by dotted lines in Figure 2. During winding of cables 37 onto drum 36, cable 38 is unwound from the drum at the same rate at which cables 37 are wound onto the drum, thus avoiding any objectionable slack in cable 38. Rotation of the drum in the opposite direction serves to wind cable 38 onto the drum while unwinding cables 37 therefrom, thus moving periscope 18 50 downward. When the periscope reaches the position shown in full lines in Figure 2, cover 14 seats upon flange 17 of trunk 13 so as to provide a watertight and pressure-resistant closure for the lower end of the trunk. Continued rotation 55 of drum 36 and winding of cable 38 thereon serves to draw the periscope 18 downward, the periscope then sliding through cover 14 as well as through the top of trunk 13. In this manner, the periscope 18 may be adjusted at any desired height 60 within control compartment 2 or within the trunk 13. In its extreme lowered or retracted position, the lower portion of the periscope is housed within trunk 27, as indicated in Figure 2A.

When the periscope is operated at medium or 65 low elevation, the eyepiece 23 thereof is disposed within control compartment 2, and the diving station and instruments within this compartment are at all times under the direct observation of the operator or commanding officer standing 70 75

upon platform 30, the commanding officer also having direct oral communication with the control compartment. With the periscope 18 in its position of maximum elevation indicated in Figure 2, the operator or commanding officer standing upon platform 30 still has direct oral communication with the control compartment 2. With periscope 18 in its uppermost position, the elevation of the objective lens thereof is as great 10 or even greater than can be obtained with a periscope fitted in the conning tower in accordance with present practice. The periscopes 10 and 18 are of such length that when fully withdrawn the tops thereof will not project above the 15 clearing lines of the boat, in accordance with the usual practice.

It is desirable that the cover 14 be held against lateral movement in its travel within trunk 13, so as to avoid subjecting the periscope to objectionable transverse stresses. This is accomplished by providing guide rollers 50 suitably mounted upon the upper face of cover 14, as in Figure 3, these guide rollers operating in channel guide members 51 extending lengthwise of trunk 13 and suitably secured to the inner face thereof. The cables 37 pass through cover 14 at opposite sides of periscope 18 in a plane extending diametrically of the periscope which, in conjunction with the disposition of the rollers 50 and guide members 51, assures smoothness in operation of the cover 14 and eliminates likelihood of binding thereof.

In the event of damage either to the periscope 18 or to trunk 13 such as would admit water to the latter, the cover 14 may be moved into lowered or closed position and the stuffing boxes 19, 43 and 46 may be tightened so as to eliminate possibility of leakage therethrough. In this manner, possibility of flooding of the boat due to damage 40 to the periscope 18 or to the trunk 13 is eliminated.

Any suitable or known means may be provided for rotating the drum 36. Conveniently, this drum is driven from an electric motor 52 through 45 a suitable gear reduction unit 53. Suitable means, of known type, is provided for controlling motor 53, for raising and lowering the periscope to the desired extent, and limit switches, of known type, may be provided for limiting the 50 extreme travel of the periscope in either direction.

What I claim is:—

1. In a submarine boat comprising a water tight and pressure resistant hull, a control compartment within said hull, a trunk extending through the upper portion of said hull and opening at its lower end into said compartment, a cover within the trunk for closing the lower end thereof, a periscope slidable through the cover and the top of the trunk, the periscope and the cover having cooperating means for causing upward movement of said cover within the trunk with said periscope, and means for raising and lowering the periscope and for moving the latter downward through the cover when the latter has been lowered into closed position.

2. In a submarine boat comprising a water tight and pressure resistant hull, a control compartment within said hull, an upper water-tight and pressure-resistant trunk extending through and above said top of the hull and opening at its lower end into said compartment, a cover within the trunk for closing the lower end there- 75 of, a periscope slidable through the cover and

the top of the trunk, the periscope and the cover having cooperating means for causing upward movement of said cover within the trunk with said periscope, a lower housing trunk within said hull disposed and adapted to receive the lower portion of the periscope when the latter is in retracted position, and means for raising and lowering the periscope and for moving the latter downward through the cover when the latter has been lowered into closed position.

3. In a submarine boat comprising a water tight and pressure resistant hull, a control compartment within said hull, an upper water-tight and pressure-resistant trunk extending through and above said top of the hull and opening at its lower end into said compartment, a cover within the trunk for closing the lower end thereof, a periscope slidable through the cover and the top of the trunk, the periscope and the cover having cooperating means for causing upward movement of said cover within the trunk with said periscope, a lower housing trunk within said hull disposed and adapted to receive the lower portion of the periscope when the latter is in retracted position, an operator's platform suspended from the cover and having an opening aligned with said lower trunk and the periscope of a size to accommodate the latter, and means for raising and lowering the periscope and for moving the latter downward through the cover when the latter has been lowered into closed position.

4. In a submarine boat comprising a water tight and pressure resistant hull, a control compartment within said hull, an upper water-tight and pressure-resistant trunk extending through and above the top of said hull and opening at its lower end into said compartment, a cover within the trunk for closing the lower end thereof, a periscope slidable through the cover and the top of the trunk, the periscope and the cover having cooperating means for causing upward movement of said cover within the trunk with said periscope, a lower housing trunk within said hull disposed and adapted to receive the lower portion of the periscope when the latter is in retracted position, an operator's platform suspended from the cover and having an opening aligned with said lower trunk and the periscope of a size to accommodate the latter, said platform being of less width than the interior of the upper trunk and of a size to pass through the lower end thereof, and means for raising and lowering the periscope and for moving the latter downward through the cover when the latter has been lowered into closed position.

5. In a submarine boat comprising a water-tight and pressure resistant hull, a control compartment within said hull, an upper water-tight and pressure-resistant trunk extending through and above the top of said hull and opening at its lower end into said compartment, a cover within the trunk for closing the lower end thereof, a periscope slidable through the cover and the top of the trunk, the periscope and the cover having cooperating means for causing upward movement of said cover within the trunk with said periscope, means for guiding the cover in its movement within the trunk, a lower housing trunk within said hull opening into the control compartment and aligned with the periscope, said lower trunk accommodating the lower portion of said periscope when the latter is retracted, a platform rigid with and suspended from the cover, said platform having an opening aligned with the

lower trunk and the periscope of a size to accommodate the latter, the lower trunk and the platform being provided with cooperating guide members for guiding said platform in the movement thereof with the cover, and means for raising and lowering the periscope and for moving the latter downward through the cover when the latter has been lowered into closed position.

6. In a submarine boat comprising a water-tight and pressure resistant hull, a control compartment within said hull, an upper water-tight and pressure-resistant trunk extending through and above the top of said hull and opening at its lower end into said compartment, a periscope 5
10
15
20
25
30
35
slidable through the top of said trunk, a lower housing trunk within said hull and opening into said compartment, said lower trunk being aligned with the periscope and adapted to receive the lower portion thereof when said periscope is retracted, the periscope normally being movable downward through the lower end of said upper trunk and the latter being adapted for reception of an operator, the lower end of said upper trunk opening directly into said control compartment in free communication therewith when said periscope is at its maximum elevation, and means for raising and lowering said periscope.

7. In a submarine boat comprising a water-tight and pressure resistant hull, a control compartment within said hull, an upper water-tight and pressure-resistant trunk extending through and above the top of said hull and opening at its lower end into said compartment, a periscope 20
25
30
35
slidable through the top of said trunk, a lower housing trunk within said hull and opening into said compartment, said lower trunk being aligned with the periscope and adapted to receive the

lower portion thereof when said periscope is retracted, a member mounted on the periscope, said member and said periscope having cooperating means for moving said member upward with the periscope when the latter has been projected to a predetermined extent while permitting relative downward movement of the periscope when it has been retracted to a predetermined extent, a platform suspended from said member for movement therewith and having an opening aligned with the lower trunk and the periscope and of a size to accommodate the latter, said platform being of materially less width than the interior of said upper trunk and of a size to pass into and out of the latter through the lower end thereof, and means for raising and lowering said periscope.

8. In a submarine boat comprising a water-tight and pressure resistant hull, a control compartment within said hull, a water-tight and pressure-resistant trunk extending through and above the top of said hull and opening at its lower end into the top of said compartment, a periscope 20
25
30
35
slidable through the top of said trunk, lower housing means within said hull opening into said compartment at the bottom thereof and adapted and disposed to receive the lower portion of the periscope when the latter is retracted, the periscope normally being movable downward through the lower end of said trunk and the latter being adapted for reception of an operator, the lower end of said trunk opening directly into said control compartment in free communication therewith when said periscope is at its maximum elevation, and means for raising and lowering said periscope.

LAWRENCE Y. SPEAR.
